TIME-DELAY PLUNGER FOR RELAYS

John P. Keating, Elkhart, and Glen L. Weimer,
South Bend, Ind., assignors to Durakool, Inc.,
Elkhart, Ind., a corporation of Indiana

Application April 20, 1946, Serial No. 663,684

4 Claims. (Cl. 175—372)

1

Our present invention relates to an improvement in relays, and more particularly to a relay providing for slow-make and quick-break of a circuit through the relay.

In the embodiment of our invention herein disclosed we have shown and described a normally open type relay comprising a casing or shell which is adapted to serve as one electrode or terminal for the relay, and in which an electrode means is mounted in insulated relation and serving as a second electrode for the relay. The casing or shell provides for the support of a main body of mercury and a plunger or displacer is contained within the casing or shell with the plunger or displacer being adapted to be normally supported in floating relation in the main body of mercury. The plunger is of a construction to provide upon the energization of the coil of the relay for slow-making of a circuit between the casing and the electrode means and upon de-energization of the coil effects the quick-breaking of a circuit through the relay.

It is an object of our invention to provide a mercury relay comprising a pair of electrode means arranged in insulated relation with respect to each other with one of the electrode means having contact with a main body of mercury, and plunger or displacer means normally disposed in floating relation in the main body of mercury in which position the main body of mercury is out of contact with the other of the electrode means, and which plunger or displacer means is adapted to be immersed in the main body of mercury upon energization of the coil of the relay to displace the main body of mercury and with the plunger or displacer means including means for effecting a time delay in contacting of the displaced body of mercury with the other of the electrode means in completing a circuit through the relay.

A further object of our invention is to provide a relay as aforesaid in which the timing means for the plunger or displacer means is operable to effect fast-breaking of a completed circuit through the relay upon de-energization of the coil thereof.

A further object of our invention is to provide a novel form of plunger means for effecting slow-make and quick-break of a circuit through a mercury relay of a character adapted to float normally in a main body of mercury for the relay with the circuit through the relay being open in the normal position of the plunger means.

The above and other objects and advantages

2

of our invention will appear from the detail description.

Now in order to acquaint those skilled in the art with the manner of constructing and utilizing relays in accordance with our present invention, we shall describe in connection with the accompanying drawings a preferred embodiment of our invention.

In the drawing:

10 Figure 1 is a detail vertical sectional view through a relay constructed in accordance with the principles of our present invention with the relay being shown in its normal open position; and

15 Figure 2 is a view of the relay of Figure 1 showing it in its closed position.

Referring now to the drawing, I have shown a relay 3 comprising a metal casing or shell 4 formed by a cylindrical tube of stainless steel or other suitable metal having a closed lower end wall 5. The casing 4 is commonly referred to in the art as an open envelope type of casing and in the embodiment of our invention herein disclosed serves as one electrode or terminal for the relay.

20 An electrode member 6 serving as a second electrode or terminal for the relay extends inwardly of the open upper end of the casing 4 and is suitably mounted in insulated and preferably gas-tight relation therein. The electrode 6 may be of any suitable form, and as shown, is imbedded in a glass bead 9 which in turn is carried in and fused to the inner surface of a metal sleeve 11. The electrode 6, the glass bead 9, and the sleeve 11 are first assembled into a unit before being

25 mounted in the open end of the tube 4. The sleeve 11 at its lower end is provided with a radially outwardly extending flange 12 which flange is adapted to seat upon an annular steel washer or stop member 13 and which in turn seats upon 30 any annular shoulder 14 preferably formed by the intersection of the enlarged counter-bore at the open end of the casing with the smaller normal bore 15 of the tube. In assembling the relay, the steel washer 13, together with the unit formed by

35 the electrode 6, the glass bead 9, and sleeve 11 are caused to occupy the position shown in Figure 1 after which a annular resilient gasket 16 of rubber or other suitable material is positioned over the sleeve 11 and seated upon the flange 12 thereof. The annular gasket 16 has an internal diameter equal to or slightly greater than the diameter of the cylindrical portion of the sleeve member 11 for fitting over the latter. If desired an annular metal plate member or washer 17 may

40 then be positioned over the sleeve 11 and seated 45 50 55

upon the top of the resilient gasket 16. With the parts in the position described, the open end of the casing 4 is then turned or spun inwardly to secure the annular member 17 in the position shown. This turning in of the open end of the casing serves to compress the annular gasket 16 between the flange 12 of sleeve 11 and the annular member 17 to form a seal at the adjacent inner cylindrical surface of the casing. In the form of relay herein disclosed this seal is not depended upon to form a gas-tight seal but rather serves principally to prevent mercury from escaping from internally of the casing. However, if desired the annular metal member 17 may be dispensed with in which case the turned in end of the casing could be caused to engage directly the resilient gasket 16 to form both a gas-tight and liquid-tight seal. When the mounting means includes the annular plate member 17 a gas-tight seal may be formed between the turned in end of the tube, the metal ring 17, and the sleeve 11 by an annular ring of solder 18 which extends from the outer periphery of the casing or tube to the sleeve 11. A lead 19, as shown, is adapted to be secured to the relay casing by means of the rings of solder 18 to provide one lead for the relay. Also a second lead 20, as shown, is secured by soldering to the outer end of the electrode 6. The mounting of the electrode 6 as above described, of itself, forms no part of our present invention and is more fully disclosed and claimed in the co-pending application of Herbert E. Bucklen, III, Serial No. 647,867, filed February 15, 1946, now Patent No. 2,450,780, granted October 5, 1948, to which reference may be had. It will be understood that this is but one form of mounting means suitable for use in practicing our present invention and that this mounting means may vary widely in form. The electrode member 6, the glass bead 9, and the sleeve 11 are preferably made of materials having substantially matching thermal coefficients of expansion to prevent breaking away of these parts from each other due to heat generated in operation of the relay. Glasses and metals having such characteristics are now well known in the art with one such metal consisting of approximately 25% nickel, 17% cobalt, 0.3% manganese and the balance of iron. Likewise suitable borosilicate glasses, otherwise known as hard glasses, are suitable for use with the metal parts made of the aforesaid alloy. Also, if desired the electrode 6 may be made of molybdenum or other suitable arc resisting metals or alloys, as desired.

The closed end 5 of casing 4, as is also known, is provided with a suitable tubulation 27 of known form and serves for evacuating the casing and filling the same with mercury. After the unit has been assembled, as described, it may be inserted in a cylindrical shell or enclosing housing 22 formed of any suitable insulating material. The open ends of the tube 22 are then filled with suitable plastic sealing composition 24 to seal the metal relay casing in the housing 22. It will be observed that the leads 19 and 20 are imbedded in the plastic sealing composition adjacent the upper end of the relay and this sealing composition is preferably of a character providing a fluid-tight seal between the several elements assembled within the open end of the casing 4 and the enclosing housing 22. This arrangement of a metal casing in a housing of insulating material of itself forms no part of our present invention and is further described in detail in the above referred to application of Herbert E. Bucklen, III.

The relay 3 further comprises an energizing coil 25 carried in a suitable supporting bracket 26 for the relay and surrounds the lower end of the tubular assembly comprising the metal casing 4 and enclosing insulating housing 22.

As previously related the casing 4 is preferably of cylindrical shape and of suitable dimensions for receiving a substantially cylindrical plunger or displacer means 30. The displacer means 30 comprises a substantially cylindrical magnetic metal sleeve member 31 formed with a reduced cylindrical upper end 32 and open at its upper and lower ends. A substantially cylindrical hollow sleeve member 33 made of suitable insulating material such as of ceramic composition commonly employed in mercury switch and relay construction is contained within the cylindrical sleeve member 31. The electrode 6 and plunger means 30 are suitably proportioned so that the electrode 6 extends into the bore of the plunger. The plunger 30 further comprises a time delay means 35 disposed at the lower end of the sleeve 31. The timing means 35 in the embodiment of our invention shown comprises a pair of spacer rings 36 and 37 between which is secured a timing disc member 38 having one or more metering orifices 39 therein, and with an end retainer plate member 42 secured between the ring 37 and the turned in flange 40 at the lower end of the sleeve member 31 to secure these parts in the position shown. The disc 38 is provided with an upwardly extending conical portion 41 and the end or retainer plate 42 is formed with a substantially downwardly extending conical portion 43 with the timing disc member 38 and the end plate member 42 together with the spacing therebetween by means of the spacer ring 37, providing a valve chamber in which a ball valve 45 formed of non-magnetic steel is disposed. The conical surface portion of the end plate 42 is provided with a plurality of bypass orifices 47. Also, the timing disc member 38 and the retainer plate 42 are provided centrally thereof with circular openings 48 and 49, respectively, which openings provide a valve seat for the ball valve 45 in each of these plate members and the purpose of which will be more fully described.

The above described assembly of the time delay means 35 in the lower end of the sleeve 31 of the plunger is effective for maintaining the ceramic liner 33 in assembled relation therewith by engagement of the upper edge thereof with the beveled shoulder 50 formed by the intersection of the sleeve 31 with the reduced upper end or collar portion 32 of the latter.

The plunger means 30, constructed as above described, has normal floating relation in a main body of mercury 51 contained in the lower end portion of the casing 4 and in its normal floating position as shown in Figure 1 floats upon the body of mercury 51 with the mercury being out of contact with the electrode member 6.

The plunger means is provided with a plurality of steel balls 52 suitably spot welded about the outer surface thereof and which are provided for guiding of the plunger 30 vertically in the relay casing 4. The construction of the plunger means embodying the plurality of steel balls 52 is further described and claimed in the co-pending application of Herbert E. Bucklen, III, and Glen L. Weimer, one of the present joint applicants, Serial No. 663,368, filed April 19, 1946, to which reference may be had. However, it will be understood that other forms of guiding means may be used for guiding the movement of the plunger means 30

in the casing within the scope of our present invention.

The operation of the above described relay is as follows:

It will be observed that in the position of the plunger means 30 as shown in Figure 1 with the coil means 25 de-energized that the relay is in normal open position with the electrode 6 being maintained out of contact with the body of mercury 51 in the lower end of the relay casing. However, upon energization of the energizing coil 25, the plunger means 30 is caused to be immersed in the body of mercury 51 in which position the plunger means 30 assumes the position shown in Figure 2 of the drawings. The valve 45 is seated on the valve seat formed by the central opening 48 in the timing disc 38 so that the displaced mercury passes through the central opening 49 of the end plate member 42 and the plurality of bypass orifices 47 thereof, and then through the one or more metering orifices 39 of the timing disc plate 38 whereupon the mercury gradually fills the bore 57 of the ceramic sleeve 33 and after a predetermined time comes into engagement with the electrode 6 to complete a circuit through the relay. The plunger means 30 is provided with the reduced collar portion 32 to prevent spilling of mercury through the upper open end of the plunger means 30 upon attraction thereof by energization of the coil to avoid short circuiting through the relay and interfering with the operation of the timing means 35.

Now with the relay in its closed position as shown in Figure 2 and upon de-energization of the coil 25 the plunger means 30 will return to its normal floating position in the body of mercury 51. However, at the start of the upward movement of plunger means 30 the ball valve 45 will be forced away from the valve seat formed by opening 48 in the disc 38 to the position shown in dotted lines in Figure 1 in which it seats upon the valve seat formed by the opening 49 in end plate 42. Thus mercury within the bore 57 will pass through the opening 48 of disc 38 and the metering orifices thereof and through the plurality of by-pass orifices 47 of end plate member 42 to effect rapid return of the mercury to its normal position in the lower end of casing 4. In this manner rapid separation of the displaced mercury with the electrode 6 is effected to provide quick breaking of a circuit through the relay. After the coil of the relay has been de-energized for a limited time the ball valve 45 will again seat on the valve seat formed by opening 48 in disc 38, as shown in full lines in Figure 1, so that upon energization of the coil 25 slow making of a circuit through the relay as first above described will be effected.

We have shown and described mercury relays of the metal casing type, but believe that it will be obvious that mercury relays having a casing or shell made of any suitable insulating material and having an electrode member extending thereto adapted to have continuous contacting engagement with the main body of mercury in the lower end of the casing may be substituted for the metal casing member 4 of the relay above described. The operation of such a relay would be the same as that of the relay described in that the plunger member would serve to establish a circuit between the electrodes when energized and to break the circuit when de-energized. In other words it will be clear that in lieu of the metal casing serving as an electrode a casing of insulating material provided with a suitable elec-

trode having contacting engagement with a body of mercury in the casing may be utilized without departing from our present invention.

While we have shown what we consider to be the preferred embodiment of our invention it will be understood that various modifications and rearrangements may be made therein without departing from the spirit and scope of our invention.

10. We claim:

1. An article of manufacture a plunger open at one end and comprising a substantially hollow cylindrical sleeve member of magnetic metal, a hollow cylindrical liner member of insulating material fitting interiorly of said sleeve member, timing means closing the other end of said plunger comprising a valve chamber having an upper plate member and a lower plate member, said upper plate member having a conical surface portion with the apex thereof disposed toward the open end of said plunger and said lower plate member having a conical portion with the apex thereof disposed in a direction opposite said upper plate member, said upper plate member having a valve seat substantially centrally thereof and having metering orifice means, said lower plate member having a valve seat substantially centrally thereof and by-pass orifice means, and a non-magnetic ball valve disposed in said chamber and movable therein for seating engagement with one or the other of the valve seats of said plate members.

2. A plunger for a mercury relay comprising a sleeve member of magnetic metal, a hollow liner 35 of insulating material fitting interiorly of said sleeve member, timing means secured between one end of said liner and the adjacent end of said sleeve member, said timing means extending transversely of said one end of said liner and 40 comprising, a first disc member having a central conical portion the apex of which extends toward said liner, a second disc member having a central conical portion the apex of which extends away from said liner whereby said disc members form 45 a valve chamber there-between at said one end of said plunger, said disc members having valve seat and orifice means in the conical portions thereof, and a ball valve in said valve chamber movable substantially axially of said plunger for cooperation 50 with said valve seat means.

3. A plunger for a mercury relay comprising a sleeve member of magnetic metal, a hollow liner of insulating material fitting interiorly of said sleeve member, timing means between one end of said liner and the adjacent end of said sleeve member comprising, a pair of superposed disc members extending transversely of said plunger and secured about their peripheries between said one end of said liner and said end of said sleeve member by a radially inwardly extending flange at said end of said sleeve member, said disc members having substantially central conical portions and arranged with the conical portion of said disc member at said one end of said liner extending in a direction toward the latter and with the conical portion of the other of said disc members extending in a direction away from said one end of said liner whereby said disc members form 65 a valve chamber therebetween at one end of said plunger, said disc members having openings centrally of the conical portions thereof forming valve seats, orifice means in said conical portions about said openings in said disc members, and a 70 ball valve of non-magnetic material in said valve

75 ball valve of non-magnetic material in said valve

17 chamber movable substantially axially of said plunger for cooperation with said valve seats.

4. A plunger for a mercury relay comprising a sleeve member of magnetic metal, hollow liner of insulating material fitting interiorly of said sleeve member, timing means between one end of said liner and the adjacent end of said sleeve member comprising a pair of superposed disc members extending transversely of said plunger and secured about their peripheries between one end of said liner and said end of said sleeve member by a radially inwardly extending flange at said end of said sleeve member, said disc members having substantially central conical portions and arranged with the conical portion of one of said disc members at said one end of said liner extending in a direction toward the latter and with the conical portion of the other of said disc members extending in a direction away from said one end of said liner whereby said disc members form a valve chamber therebetween at said one end of said

18 plunger, said one disc member having a valve substantially centrally of the conical portion thereof and metering orifice means, said disc member having a valve seat substantially centrally of the conical portion thereof, a pass orifice means, and a ball valve of non-magnetic metal in said valve chamber, movable substantially axially of said plunger for cooperation with said valve seats.
